UNITED STATES PATENT OFFICE

2,520,254

RESCORING APPARATUS FOR GOLF CLUBS

Oliver W. Partain and Elmer M. Lang, Tulsa,
Okla.; said Lang assignor to said Partain

Application July 10, 1948, Serial No. 38,118

6 Claims. (Cl. 90—38)

1

This invention relates to apparatus for rescoring golf clubs and more particularly to a combination tool and fixture for straightening the edges and otherwise rescoring the grooves in the striking face of "iron" golf clubs.

Golf clubs, particularly those called "irons" usually have grooves on the striking face, said grooves being longitudinally of the face or perpendicular to the direction of travel of the club face when striking a ball. New clubs have relatively sharp edges on the grooves and tend to add to the "bite" of the club onto the ball and add to the "back spin" imparted to the ball. After considerable use, the edges of the grooves become peened over until the grooves are not of conventional width and depth and the clubs have less tendency to place a spin on the ball. Due to the change in the ability of the club to place a spin on the ball, many golf players sell or trade their clubs and obtain new ones, however, actually the old clubs are efficient as far as weight and balance and if the grooves are made uniform or recut to conventional width and depth, said old clubs would function substantially as well as new ones.

The objects of the present invention are to provide an apparatus for regrooving golf clubs to restore substantially the original ability of said clubs to place a spin on the ball; to provide apparatus for clamping a golf club in a fixture and aligning a guide with the respective grooves for reciprocation of a cutting tool in said grooves to make same of suitable uniform size and shape; to provide guide means for maintaining the grooves parallel; to provide a simple fixture and cutter easily applied, adjusted and operated for rescoring any conventional "iron" golf club; and to provide a golf club rescoring device adapted for hand use by unskilled persons to effectively restore the uniformity of grooves in golf clubs.

In accomplishing these and other objects of the present invention, we have provided improved details of structure, the preferred forms of which are illustrated in the accompanying drawings, wherein:

Fig. 1 is a perspective view of the rescoring apparatus applied to the head of a golf club "iron."

Fig. 2 is an elevational view of the apparatus showing the guide means aligned with a groove in the golf club.

Fig. 3 is a rear elevation, particularly illustrating the position of the clamping means on the fixture.

Fig. 4 is a bottom view of the apparatus, por-

2

tions being broken away to illustrate the locking of the guide means to the fixture.

Fig. 5 is an end elevation of the apparatus illustrating the engagement of the striking face 5 of the club with the portions of the fixture.

Fig. 6 is a perspective view of the cutting tool used for the rescoring of the clubs.

Fig. 7 is a perspective view of a modified form of rescoring tool.

10 Fig. 8 is an elevation of the rescoring tool in position for engaging a groove of a club.

Referring more in detail to the drawing:

1 designates apparatus for rescoring the grooves in golf clubs generally consisting of a fixture 2 adjustably mounting a guide bar 3 for guiding a scoring tool 4 which is moved along the guide bar in the rescoring of the grooves 5 in the striking face 6 of the head 7 of the type of golf club 8 commonly called "irons."

20 The fixture 2 includes a back plate 9 of substantially the same length as the blade forming a part of the golf club head and of suitable width to provide a boss 10 adjacent the free edge 11 of said back plate substantially centrally disposed

25 relative to the golf club head. The boss 10 has a threaded bore 12 for mounting a setscrew 13 preferably including a wing type head 14 whereby the screw may be turned into engagement with a club head as later described. The edges

30 10 of the back plate converge toward the opposite edge 15 to reduce the metal required and facilitate the placing of a golf club in the fixture. The opposite edge 15 is preferably straight and substantially parallel with the heel 16 of the golf club head.

35 Flanges 17 and 18, preferably integral with the back plate and arranged at the ends thereof adjacent the edge 16, extend forwardly of said back plate, said flanges being perpendicular to

40 the forward face 19 of said back plate. The flanges terminate in upwardly extending parallel arms 20 and 21, preferably having rear faces 22 parallel to the forward face 19 on the back plate, the faces 22 being spaced from the face 19 suffi-

45 ciently to permit the insertion of the head of any conventional "iron" golf club therebetween, with the heel of the golf club resting on the flanges 17 and 18. The arms 20 and 21 are preferably so arranged that the spacing between the inner edges 23 and 24 thereof is greater than the grooved portion of the striking face on the golf club head. The adjacent portions of the rear faces 22 of the arms 20 and 21 are cut away to provide recesses 25 and 26 extending the full

50 length of said arms, said recesses being of suit-

55 length of said arms, said recesses being of suit-

able depth to receive the guide bar 3 therein, wherein said guide bar may be moved across the width of the face of the club with the rear face 28 of said guide bar slightly spaced from the striking face 6 of the club head to provide clearance facilitating the moving of said bar. Arranged adjacent the ends of the guide bar are threaded bores 29 aligning with slots 30 and 31 in the arms 20 and 21, whereby shanks 32 of setscrews 33 extend through the respective slots and are threadedly engaged in the threaded bores 29 of the guide bar, said setscrews having heads 34 adapted to engage the forward face 35 of the arms 20 and 21 to clamp the guide bar to said arms. The guide bar is preferably provided with a longitudinal slot 36 which is wider than the grooves of the club and of suitable width to slidably receive the end 37 of the rescore tool 4 adapted to be moved along the slot 36 to cut the grooves in the striking face of the club head.

The scoring tool preferably consists of a handle portion 38 having a frustro-conical portion 39 on one end thereof, the small end of the frustro-conical portion terminating in a shank 40, the end 37 of which is flattened or cut to provide parallel sides 41 and 42 and a thickness of slightly less than the width of the slot 36 and of greater width than the groove to be cut in the striking face of the club, whereby the end face 43 of said shank will engage the face of the club at the sides of the groove to be cut. The shank 40 is provided with a socket extending therein from the face 43 and adapted to receive a cutter 44 therein. The cutter projects from the face 43 a distance equal to the regulation depth of the club grooves, and is of a width equal to the regulation width of said grooves. The end of the cutter 44 is provided with a V-shaped cut 45, so arranged that the intersection of the V-shaped cut with the edges of the flattened portion of the shank 40 form cutting edges 46. Said tool preferably is hardened to enhance the cutting ability of the tool.

In using a tool constructed as described, the setscrew 13 is turned to back same into the back plate 9 sufficiently for the insertion of a golf club head between the back plate 9 and the arms 20 and 21. The head of the golf club is then inserted between the faces 19 and 22 with the striking face 6 in engagement with the faces 22 and the heel 16 of said club resting on the flanges 17 and 18. The setscrew 13 is then turned to move the ends 46 thereof into engagement with the back of the club head to clamp the striking face against the faces 22 of the arms 20 and 21. The screw 13 preferably is arranged at a suitable angle relative to the back plate as shown in Fig. 5, whereby the clamping force of said screw tends to hold the heel of the club in engagement with the flanges 17 and 18, this angular arrangement being desired due to the fact that most clubs are thicker at the bottom or heel edge to provide weight in the club head. The setscrews 33 are then loosened to permit free movement of the guide bar 3, which is then moved with the set-screw shanks sliding in the slots 30 and 31 to position the slot 36 in alignment with a groove in the club face. It is preferable to start with the first groove at either the top or the bottom of the club face. When the slot 36 aligns with the groove, the setscrews 33 are tightened to securely lock the guide bar in place. The rescore tool is then inserted whereby the faces 41 and 42 substantially engage the sides of the guide bar slot and the end face of the shank 40 engages

the striking face of the club and the cutting edges 46 engage in the groove of said golf club. Reciprocal movement of the rescore tool longitudinally of the guide bar while applying pressure on said tool to force same into the groove and the end face 43 in engagement with the striking face of the club causes the respective cutting edges 46 to cut metal from the sides and bottom of said groove. If the slot 36 is properly arranged and aligned relative to the groove in the club, said groove will remain a standard width as determined by the width of the cutting tool 44. After cutting or rescore one groove, the setscrews 33 are loosened and the guide bar moved in the recesses 25 and 26 to align with the next succeeding groove and the process repeated. This is continued until all the grooves in the striking face are rescored. The setscrew 13 is then turned to back same from engagement with the club head to permit removal of the club head from the fixture which is then ready to receive the next club to be processed.

The modified form of rescore tool shown in Figs. 7 and 8 consists of a handle portion 47 terminating in a shank 48 arranged at an angle to the handle. The shank is flattened to provide parallel sides 49 of a portion of slightly less width than the slot 36 whereby said portion may be moved in said slot with the end face 50 of the shank engaging the striking face of the club. Secured in a socket 51 in the shank is a cutter 52 having substantially the same width as the grooves to be cut and projecting from the shank face 49 the amount of the regulation depth of said grooves. The cutter 52 is relieved on the trailing portion to facilitate cutting action. The corners or end edges of the face 49 are arranged on radii as at 53 to prevent destroying of the wire edges produced at the side edges of the grooves by the cutter.

It is believed obvious that we have provided a simple, efficient rescore apparatus capable of accurately cutting the sides and bottom of the grooves in used golf clubs to restore same to substantially their original efficiency in placing spin on the ball being struck.

What we claim and desire to secure by Letters Patent is:

1. Apparatus for rescore the grooves in golf clubs comprising, a clamp having spaced parallel arms, means on the clamp for engagement with a head of a golf club for clamping said head against the parallel arms, a guide having a slot therein slidably mounted on the arms and substantially engaging the face of a golf club and movable thereover to selectively align the slot with the grooves in said club, means for locking the guide in selected position, a cutting tool slidably in said slot, and cutting edges on said tool adapted for engagement in the selected groove for cutting action therein in response to movement of said tool in the slot.

2. Apparatus for rescore the grooves in golf clubs comprising, spaced parallel arms adapted to engage the striking face of a golf club, means adapted for engagement with said club head to clamp the head against the arms, a guide bar having a slot therein slidably mounted on said arms for movement over the face of a golf club to selectively align said bar with the grooves in said club, said bar substantially engaging the grooved portion of the striking face of the golf club, means for clamping the bar to the arms in selected position, and a cutting tool slidably in the guide bar slot and engaging in the club

grooves for cutting same in response to movement of said tool along said guide bar.

3. Apparatus for rescoreing the grooves in golf clubs comprising, spaced parallel arms adapted to engage the striking face of a golf club, a back plate spaced from said arms and integral therewith whereby a golf club engaging the arms is between the plate and arms, means adapted for engagement with said club head to clamp the head against the arms, a guide bar slidably mounted on said arms for movement over the face of a golf club to selectively align said bar with the grooves in said club, means for clamping the bar to the arms in selected position, a tool adapted for sliding engagement with the guide bar, and cutting edges on said tool adapted to engage in the club grooves for cutting same in response to movement of said tool along the groove.

4. Apparatus for rescoreing the grooves in golf clubs comprising, spaced parallel arms adapted to engage the striking face of a golf club, a back plate spaced from said arms and having connection therewith whereby a golf club engaging the arms is between the plate and arms, means on the back plate adapted for engagement with said club head to clamp the head against the arms, a guide bar having a slot therein slidably mounted on said arms for movement over the face of a golf club to selectively align said slot with the grooves in said club, means for clamping the bar to the arms in selected position, a tool slidably in the guide bar slot, and cutting edges on said tool adapted to engage in the club grooves for cutting same in response to movement of said tool along said grooves.

5. Apparatus for rescoreing the grooves in golf clubs comprising, spaced parallel arms adapted to engage the striking face of a golf club, said arms having a slot therein transversely of the grooves in the club engaged by said arms, a back plate spaced from said arms and having connection therewith whereby a golf club head engaging the arms is between the plate and arms, means in the back plate adapted for engagement with said club head to clamp the head against the arms, recesses in the arms, a guide bar having a slot therein and having its ends slidably

mounted in said recesses for movement over the face of the golf club to selectively align the slot with the grooves in said club, means in said bar extending through the slots in the arms for clamping said bar in selected position, a tool slideable in the guide bar slot, and cutting edges on said tool adapted to engage in the club grooves for cutting same in response to movement of said tool along said grooves.

10 6. Apparatus for rescoreing the grooves in golf clubs comprising, spaced parallel arms to engage the striking face of a golf club, said arms having a slot therein transversely of the grooves in the club engaged by said arms, a back plate spaced from said arms and integral therewith whereby a golf club head engaging the arms is between the plate and arms, an angularly arranged setscrew threadedly mounted in the back plate adapted for engagement with said club head to clamp the head against the arms, recesses in the arms, a guide bar having a slot therein and having its ends slidably mounted in said recesses for movement over the face of the golf club to selectively align the slot with the grooves in said club, said bar having threaded bores adjacent the ends thereof and aligning with the slots in the arms, screws extending through the slots in the arms and threaded into the threaded bores for clamping said bar to the arms in selected position, a tool slideable in the guide bar slot, and cutting edges on said tool adapted to engage in the club grooves for cutting same in response to movement of said tool along the grooves.
